UNITED STATES PATENT OFFICE.

WILLIAM RODERICK BARCLAY, OF LEICESTER, ENGLAND, ASSIGNOR TO UNITED SHOE MACHINERY CORPORATION, OF PATERSON, NEW JERSEY, A CORPORATION OF NEW JERSEY.

SHOE.

Application filed August 24, 1926, Serial No. 131,284, and in Great Britain September 1, 1925.

This invention relates to shoes and particularly to the heel portion of a boot or shoe.

Customarily the comparatively low heels

5 of men's shoes, for example, are made of leather or leatherboard and any cushioning action that is desired is obtained by the attachment of rubber treads. Sometimes a whole cushion heel is employed, and the patent to Cooke No. 1,530,301, granted March 17, 1925, discloses such a whole cushion heel in which the weight has been reduced and attachment by customary methods facilitated by the use of a plywood core. The present invention is, in one aspect, particularly applicable to heels of the type disclosed in the said patent, although certain features of the invention are capable of adaptation to other types of whole heels.

20 Shoes having whole cushion heels have a disadvantage in that it is difficult, if not impossible, so to finish the heel portion of the shoe that a contrast in color or polish is not apparent where the yielding material of the 25 rear and side surfaces of the heel meets the edge of the outsole on the heel-seat of the shoe. It is an object of the present invention to overcome this difficulty without affecting disadvantageously the structure of 30 the shoe or unduly adding to the cost of its manufacture.

With the described object in view an important feature of the invention consists in a shoe to which is attached a cushion heel 35 the yielding material of which extends from the tread of the heel to the shoe upper, around the side and back of the heel, except at the breast end of the heel, and conceals the adjacent margin of the heel-seat portion 40 of the sole.

In the illustrated embodiment of the invention the marginal portion of the heel-seat end of the outsole is cut away from a point near one breast corner of the heel to a 45 point near the other breast corner, leaving a margin of the shoe upper exposed on the shoe bottom. The heel is provided on its attaching face with a marginal rim integral with the yielding material of the cushioning 50 body portion of the heel and adapted to contact with the shoe upper. Space within the rim comprises a hollow adapted to receive the reduced rear end of the outsole the edge of which is concealed by the aforesaid rim 55 so that the visible edge of the attached

heel, from the tread thereof to the shoe upper, consists of a single material which may easily be finished to give a uniform appearance.

The various objects and features of the invention will be best understood and appreciated from the following description in connection with the accompanying drawings of one form of shoe and heel illustrative of the invention the scope of which will be defined in the appended claims.

In the drawings,

Fig. 1 is a top plan view of one form of heel constructed in accordance with the invention;

Fig. 2 is a top plan view of a modified form of heel;

Fig. 3 is a cross-section of the heel shown in Fig. 1; and

Fig. 4 is a side elevation of the heel end of a shoe with the heel attached thereto.

Referring now to the drawings, the illustrative heel 1 may be assumed to be one of the type disclosed in the above-mentioned patent but instead of the rubber that surrounds the core at the sides 3, 5 and the rear 7 of the heel terminating at about the level of the upper surface of the core 9, the rubber is continued upward to form a rim 11 extending well above the core. This results in the formation of a hollow 13 to receive the rear end of the outsole 15 and conceal its marginal edge which, from points adjacent to the breast corners of the heel, may be beveled to correspond to the bevel of the rim 11.

As illustrated, the rim 11 has an upper surface of substantial width adapted to contact with and make a tight joint with the adjacent surface of the shoe upper. This built-up and flexible portion or rim 11, as shown, 95 overlaps the core 9 as at 17 so as to assist in bonding the rubber cover to the core but may terminate near the margin of the core to leave the central portion of the latter exposed or covered with a mere skim of rubber 19, Fig. 3. The upper surface of the heel may, in the result, be a smoothly curved hollow or the curvature of the hollow may be broken near its margin as at 21 where the inner surface of this built-up portion rises 100 105 comparatively steeply.

The hollow 13 may be partially filled in with rubber, as shown at 23 in Fig. 1, by an inward extension of the rim 11 in order to permit shortening of the outsole to save the 110

comparatively expensive sole leather, or it may extend rearwardly, as shown in Fig. 2. The rim 11 of the heel may cease, as illustrated at 27, just short of the breast edge of the heel, in which case the sole will extend at those points to fit into the angle between the surface of the heel and the rim 11; thus the sole will be prevented by the heel from sagging at the edges as it might do if the rim 11 extended to the heel breast and the edges of the sole were therefore left unsupported.

The shoe may be prepared for the reception of the heel by cutting away the marginal portion of the heel-seat of the outsole from a point near one breast corner to a point near the other so as to leave a horse-shoe or other margin of upper exposed on the shoe bottom, the heel being then attached from the outside or from the inside by nails or other fastenings which penetrate through or into the core 9 and also penetrate both the outsole and the insole.

The result is that around the heel end of the sole the rim 11 embraces more or less closely the upper of the shoe and conceals the sole edge from a point near one breast corner to a point near the other. The comparative resilience of the rim 11 permits the securing of a snug fit of the heel to the upper of the shoe by deformation of the yielding rim during the heel-attaching operation without detriment to those conjoint qualities of resilience in use with stability in attachment and wear which characterize the cored type of heel.

The built-up portion 11 may be formed in one molding operation with the heel as a whole or may be united to the heel or built up on it after the heel has been formed and may or may not be of the same composition as the resilient covering or body of the heel. In some instances a difference of flexibility may be obtained by a difference of composition but manifestly it will be preferable to retain a sufficient similarity in nature to insure the whole of the rear and side walls of

the heel behaving similarly under finishing treatment.

The attaching nails or other fastenings will preferably, as usual, penetrate the heel as close to its margin as practicable and may therefore pass just inside the overlap 17 or, where that extends inwardly to a sufficient extent, may pass through it.

The heel may have its built-up portion 11 ornamented by molding or otherwise. For example, it may be finished with a seat beading 29 such as would have been applied to the edge of the sole of the shoe to which the heel was attached had the margin of the sole not been trimmed away.

Having described the invention, what is claimed as new and desired to be secured by Letters Patent of the United States is:

1. A shoe having an upper, an outsole and a cushion heel of yielding material, said yielding material concealing the edge of the heel-seat end of the sole except at the breast end of the heel, where the entire width of the sole overlaps the heel for a short distance.

2. A cushion heel comprising a core and a covering of rubber encasing the sides and bottom of the core, said rubber extending upward above the top surface of the core to form a sole end receiving hollow extending from the breast of the heel rearwardly for a distance substantially less than the length of the heel.

3. A cushion heel comprising a core and a covering of rubber encasing the sides and bottom of the core, said rubber extending above the top surface of the core to form a rim of the thickness of a shoe sole overlapping the edge of the core, the top surface of the core being exposed inside of the overlapping rim and the rim and exposed surface of the core forming a sole end receiving hollow.

In testimony whereof I have signed my name to this specification.

WILLIAM RODERICK BARCLAY.
